UNITED STATES PATENT OFFICE

EDWARD WILSON, OF ST. LOUIS, MISSOURI

COMPRESSOR OR PUMP

Application filed April 8, 1929. Serial No. 353,379.

This invention relates to compressors or pumps and consists of the new and useful arrangement, combination and construction of parts herein described and claimed.

- 5 An object of the invention is to provide a machine for use as a compressor or pump and comprising a stationary cylinder head surrounded by a cylinder which cooperates with the head to form a compression chamber, in combination with a shaft supported for rotation in a novel and efficient manner whereby the resistance to rotation of the shaft is minimized, and novel means for operating said cylinder by said shaft.
- 10 Another object is to provide a machine improving generally the construction, relationship and arrangement of parts disclosed in my companion application Serial No. 303,400, filed September 1, 1928.
- 15 Other objects will appear from the following description, reference being made to the drawings in which

Fig. 1 is a vertical sectional view of my improved machine.

20 Fig. 2 is a cross sectional view approximately on the line 2—2 of Fig. 1.

Fig. 3 is a sectional view approximately on the line 3—3 of Fig. 2 showing the construction and arrangement of the outlet passage from the compression chamber for the compressed air or gas.

25 Fig. 4 is a sectional view showing the inlet or return passage to the compressor.

The machine shown comprises a base 1 having an upwardly extended cylindrical head 2 rising from a smooth radial end wall 3.

30 A frame comprising a vertical portion 4 which is preferably circular in cross section and a web 5 having a central bearing support 6 is attached to the base 1 by bolts 7 and is enclosed within a housing 8 fastened to the base 1 by bolts 9. The bearing support 6 is in vertical axial alinement with a bearing support 10 formed in the base 1 below the plane of the head 2. An electric motor 11 is attached to the support 4 within the housing 8 and wires 12 for said motor enter the housing through a removable plate 13. A cylinder 14 is mounted around the head 2 and is operative to compress the air or gas

35 entering the space between the cylinder and the head. The internal diameter of the cylinder is greater than the diameter of the head 2. The lower end of the cylinder 14 operates in close contact with the smooth radial wall 3 formed on the base 1. The upper end of the cylinder 14 has an end wall 15 extending radially toward the axis and operating in close contact with the upper end of the head 2.

40 One side of the head 2 is formed with a wide radial slot 16 extending the full length of the head from the wall 3 to the cylinder end wall 15. A plate or blade 17 is mounted for radial sliding movements in said slot. A cup retainer 18 is mounted for sliding movements in a cylindrical hole 19 in the inner edge of the plate or blade 17 and encloses a spring 20 having one end bearing against the inner end wall of said cup retainer and the opposite end bearing against the bottom of the hole 19 in the plate or blade 17.

45 A shaft 21 is connected with the motor 11 for rotation thereby. This shaft projects 75 downwardly through the head 2 and has affixed thereto a ring 22 so that said ring rotates with said shaft. A ring 23 is concentric with the ring 22 and has floating fit or bearing within the bearing support 6. A 80 series of antifriction bearing elements 24 are mounted and retained between the rings 22 and 23. The lower end of the shaft 21 within the bearing support 10 has affixed thereto a ring 25. The portions of the shaft 21 85 on which the rings 22 and 25 are secured are in axial alinement. A ring 26 is rotatively mounted in the bearing support 10 and seats upon a shoulder 27. A series of antifriction elements 28 are supported and maintained 90 between the rings 25 and 26. Thus, the bearing at the lower end of the shaft constitutes an antifriction bearing to minimize frictional resistance to rotation of the shaft and also constitutes a thrust bearing for said 95 shaft.

50 The shaft 21 is formed with an eccentric portion 29 terminating above the ring 25 so that said eccentric portion is out of contact with said ring. The cylinder 14 has a con- 100

centric hub 30 which extends downwardly into but out of contact with the head 2. On said eccentric portion 29 a ring 31 is rigidly secured having its upper end clamped against a circumferential flange 31^a above the eccentric portion 29. A ring 32 has floating fit against the inner periphery of the hub 30 and between said rings 31 and 32 a series of anti-friction elements 33 are supported and maintained. The ring 31 is above a ring 34 on the eccentric 29 and above the ring 25. The clamping nut 25^a screwed on the lower end of the shaft 21 supports the ring 25 and clamps the ring 34 against the ring 31 and 15 clamps the ring 31 against the circumferential flange 31^a. Thus, by the close engagement of the rings 25 and 31 on the shaft and by the clamping device therefor said rings 25 and 31 are held rigid with the shaft. 20 The cup retainer 18 for the spring 20 has its inner end seated against the periphery of the hub 30 so that said spring 20 is maintained under uniform tension and holds the outer edge of the plate or blade 17 in permanent contact with the inner periphery of the cylinder 14. The cylinder end wall 15 has therethrough holes 35 for the passage of oil into the head 2 and about the hub 30. And the cup retainer 18 is preferably formed 25 with a hole 36 in its inner end to permit flow of oil into and from said cup.

The passage 37 through the head 2 admits air or gas into the space between the cylinder 14 and the head 2. An outlet passage 38 is 30 provided for the compressed air or gas. The passage 38 opens into a pipe 39 projecting upwardly through the web 5 to a height well above the oil level indicated by the line 40 (Fig. 1). The passage 39 is controlled by a 35 valve comprising a disc 41 (Fig. 3) mounted in a valve chamber 42 and pressed to closed position by a spring 43. Extent of movement of the spring 43 is limited by the spring support 44 removably screwed into the base 1.

40 When the machine is in use it is kept filled with oil to about the line 40 which is above all of the bearings for the shaft 21 but below a counterweight 45 attached to the shaft 21 to counterbalance the eccentric 29 and the 45 connected parts. Since the counterbalance weight 45 is above the oil level it meets with no resistance by the oil. The bearing supported by the web 5 and the bearing for the lower end of the shaft stabilize the shaft, 50 prevent vibration, reduce friction and obtain maximum ease of operation. These types of bearings permit free circulation and passage of the oil therethrough so that the parts are maintained in a perfectly lubricated condition 55 all of the time. Free circulation of the oil into and out of the well 46 below the lower end of the shaft is further obtained through a port 47. Thus the circulation of the oil is 60 made easy and maximum efficiency in operation is obtained.

When the machine is running the cylinder 14 is operated eccentrically about the stationary head 2 with the result that the air or gas entering the cylinder, that is to say, the compression chamber between the cylinder and the head, through the port 37, is compressed and discharged through the port 38, being controlled somewhat by the valve 41. The compressed air or gas is discharged into the housing 8 above the oil level 40 by means of the pipe 39 and is conducted to any point of use through an outlet pipe 48. Obviously, the machine may be equipped with a return pipe (not shown).

70 From the foregoing it is clear enough that the invention obtains all of its intended objects and purposes in a highly efficient and satisfactory manner and that no unusual or difficult manufacturing problems are involved. Since the operation and function of 75 the machine are now apparent, I claim and desire to secure by Letters Patent:—

80 1. A compressor or pump comprising a stationary cylindrical head, a bearing below and a bearing above said head, a shaft extending through said head and journaled for rotation in said bearings, means for supporting said shaft by said bearings, an eccentric 85 on said shaft between said bearings and partly enclosed by a part of said means, a cylinder 90 enclosing said head and cooperating therewith to form a compression chamber, a hub on said cylinder extending into said head, a ring having floating fit within said hub for operating said hub about said head, and anti-friction devices for operating said ring by a 95 part of said shaft supporting means.

100 2. A compressor or pump comprising a stationary cylindrical head, an antifriction bearing below and an antifriction bearing 105 above said head, a shaft extending through said head and journaled for rotation in said bearings, means cooperating with said bearing that is below said head for supporting said shaft, a cylinder enclosing said head and 110 cooperating therewith to form a compression chamber, an antifriction bearing ring enclosing and operated by a part of said means, and means controlled by said antifriction ring for operating said cylinder eccentrically 115 about said head.

120 3. A compressor or pump comprising a stationary cylindrical head, a bearing below and a bearing above said head, a shaft extending through said head and journaled for rotation in said bearings, an eccentric on said shaft 125 between said bearings, means mounted on said eccentric and cooperating with said bearing that is below said head for supporting said shaft, a cylinder enclosing said head and co-operating therewith to form a compression chamber, a hub in connection with said cylinder extending into said head and about a part of said means, and an antifriction device 130 between said means and said hub for

operating said hub eccentrically within said head.

4. A compressor or pump comprising a stationary cylindrical head, a bearing below and 5 a bearing above said head, a shaft extending through said head and journaled for rotation in said bearings, an eccentric on said shaft between said bearings, means mounted on said eccentric and cooperating with said bearing 10 that is below said head for supporting said shaft, a cylinder enclosing said head and cooperating therewith to form a compression chamber, a hub in connection with said cylinder extending into said head and about a 15 part of said means, an antifriction device between said means and said hub for operating said hub eccentrically about said head, a plate or blade mounted for radial movements in said head, and means controlled by said hub 20 for pressing said plate radially into contact with the inner periphery of said cylinder.

5. A compressor or pump comprising a base, a cylindrical head rigid with and rising from said base, said base having a cavity 25 therein below said head and having a passage opening laterally into said cavity, a bearing supported in said cavity, a bearing supported above said head, a shaft journalled for rotation in said bearings and extending 30 through said head, elements mounted on said shaft and cooperating with said first bearing to support said shaft, a cylinder enclosing said head and cooperating therewith to form a 35 compression chamber, and means for operating said cylinder about said head to effect compression of fluid in said compression chamber.

6. A compressor or pump comprising a base, a cylindrical head rigid with and rising 40 from said base, said base having a cavity therein below said head and having a passage opening laterally into said cavity, a bearing supported in said cavity, a bearing supported above said head, a shaft journalled for rotation in said bearings and extending through 45 said head, elements mounted on said shaft and cooperating with said first bearing to support said shaft, a cylinder enclosing said head and cooperating therewith to form a 50 compression chamber, means for operating said cylinder about said head to effect compression of fluid in said compression chamber, a housing confining a body of oil about all of said parts, and means for conducting compressed 55 fluid from said chamber into said housing above said oil.

7. A compressor or pump comprising a rigid base having a cavity in its upper side and a passage opening laterally into said 60 cavity, a cylindrical head extending upwardly from said base, a cylinder enclosing and cooperating with said head to form a compression chamber, a bearing supported in said cavity, a bearing mounted above said 65 cylinder, a shaft journalled in said bearings,

means for supporting said shaft by said first bearing, a motor for rotating said shaft, mechanism for operating said cylinder about said head by said shaft, a housing for confining a body of oil about said head and said bearings and in communication with said passage to said cavity, and means for conducting compressed fluid from said cylinder into said housing above said body of oil.
